(57) **CLAIM**

The ornamental design for a fishers lipped stinger grip hook, as shown.

DESCRIPTION

A portion of the disclosure of the patent document contains material to which a claim for copyright is made. The copyright owner has no objection to the facsimile reproduction by anyone of the patent document or the patent disclosure, as it appears in the Patent and Trademark Office patent file or records, but reserves all other copyrights whatsoever.

FIG. 1 is a front perspective view of a fishers lipped stinger grip hook showing my new ornamental design.

FIG. 2 is a rear perspective view thereof.

FIG. 3 is a top view thereof, the bottom view being a mirror image thereof.

FIG. 4 is a rear view thereof.

FIG. 5 is a front view thereof;

FIG. 6 is a side view thereof; and,

FIG. 7 is an opposite side view.
